PAPER MACHINE SLITTER KNIFE

Albert John Thibedeau, Ottawa, Ontario, Canada

Original application July 5, 1934, Serial No. 733,777, Patent No. 2,043,818. Divided and this application August 20, 1935, Serial No. 37,017

6 Claims. (Cl. 164—60)

This invention relates to improvements in machines for slitting the paper web as it is being wound or cut to size and as to the regulation of this machine by remote control.

5 This invention is a division of my application Serial Number 733,777 filed July 5, 1934, for Paper machine slitter knives.

In carrying out my invention, I propose to avoid the danger to the operator in threading 10 and to reduce the operating costs by the adjustment of the slitter knives to operative or inoperative position by electrical means under remote control. One or more knives may be adjusted simultaneously, individually or in predetermined 15 groups.

One of the objects of my invention is to reduce the time required to thread the various elements of the machine.

Another object is to reduce the hazard of accidents.

Still another object of the invention is to increase the length of life of the slitter knives.

A still further object of the invention is to vary the width of the slit material by throwing either in or out of operation the desired slitter knives.

Other objects will appear more fully hereinafter.

Referring to the drawing:

30 Figure 1 is a sectional view of a slitter and controlling mechanism using a solenoid and plunger.

Figure 2 is a sectional view of a slitter and controlling mechanism using an electric motor.

35 I propose to utilize a slitter of the shear cutting type. The device consists of a mechanism which actuates the movable slitter shaft 1 in a longitudinal direction either directly or through levers or other mechanical means. For instance, the slitter shaft 1 may be moved by a solenoid 2 and plunger 3 or by a motor 4, gear 5 and rack 6. The solenoid 2 is operated by passing an electric current (D. C.) through the coil which sets up an electric field forcing the plunger 3 outwards.

40 To return the cutter 7 to operating position the current is cut off and the spring 8 between bracket 9 and collar 10 causes the mechanism to be returned to the original position. In the modified form of electrical control, the small electric motor 4 when the switch is thrown it rotates gear 5 in such a manner that the rack 6 moves outwards rocking rocker arm 4' to move cutter 7. On reversing motor 4, the mechanism will be brought back by reversing the process and as the 45 reduction of pressure on the upper end of rocker

arm 4' takes place spring 8 assists in the returning of cutter 7 to position. Solenoid 2 and plunger 3 may be connected directly to slitter shaft 1 or may act directly through the bracket 9 onto the inner housing of the slitter bearing 12.

According to my invention, the entire apparatus is manually operated through a remote control.

As described in application Serial Number 733,777, the one remote control may govern all 10 the slitter knives and place them in threading or operating position, or control each individual knife or group of knives.

It should be noted that the pressure of the slitter knives is controlled by spring 8, and the 15 adjustment of spring 8 through the adjustment of spring housing in cooperation with bracket 9 determines the predetermined pressure. Furthermore, this pressure is not altered by reason of the change from operative to inoperative position and back again so that considerable time is saved as the slitter knives are ready for operation as soon as the threading is completed and the knives are electrically returned to position through remote control. Furthermore, the manual spreading by driving in a wedge between the knives and the top slitter as is generally customary is avoided. This is a dangerous operation. In addition, the time for threading is reduced and the web need not be broken in order to make 20 adjustments. Also varying widths may be slit by the predetermined throwing out of operation of slitter knives. Where this can be done a considerable saving in labor cost can be had.

25 What I claim is:

1. In a paper machine, a slitter mechanism comprising a plurality of slitter knives, means for adjusting the slitter knives at a fixed predetermined pressure, electrically operated means for shifting said knives laterally by remote control and releasing said electrically operated means and returning said slitter knives to operating position by the said means for adjusting the said slitter knives at a fixed predetermined pressure.

2. Slitter mechanism for paper machines comprising a shaft, a rotary slitter knife carried by said shaft, means including an electrical unit for shifting the shaft and knife to an inoperative position for the latter.

3. Slitter mechanism for paper machines comprising a shaft, a rotary slitter knife carried by said shaft, means including an electrical unit for shifting the shaft and moving the knife to an inoperative position.

4. Slitter mechanism for paper machines comprising a shaft, a rotary slitter knife carried by said shaft, means for normally holding the slitter knife in operative position, and means including 5 an electrical unit for shifting the shaft and moving the knife to inoperative position.

5. Slitter mechanism for paper machines comprising a shaft, a rotary slitter knife carried by said shaft, means for normally holding the slitter 10 knife in operative position, and means including an electrical unit for shifting the shaft and moving the knife to inoperative position, and a remote control for the electrical unit.

6. In a paper machine, a slitter mechanism comprising a plurality of holders, a slitter knife in each holder, an electric motor for each holder so positioned as to move its individual slitter knife from operative to inoperative or threading position independent of the movement of the others, means to hold the knife in cutting position when the motor is inoperative, and remote control for each motor.

ALBERT JOHN THIBEDEAU.
